US0D1085458S

(12) **United States Design Patent** (10) **Patent No.:** **US D1,085,458 S**
(45) **Date of Patent:** **** Jul. 22, 2025**

(54) **REAGENT CARTRIDGE**

- (71) Applicants: **Illumina, Inc.**, San Diego, CA (US);
Illumina Singapore Pte. Ltd.,
Singapore (SG)
- (72) Inventors: **Erik Allegoren**, San Diego, CA (US);
Emerico Alberto Brewer, Chula Vista,
CA (US); **Robert Nicholas Dean**, San
Diego, CA (US); **Max Warren Pollock**,
San Diego, CA (US); **Bashkaran
Subramanian**, Singapore (SG)
- (73) Assignees: **Illumina, Inc.**, San Diego, CA (US);
Illumina Singapore Pte. Ltd.,
Singapore (SG)
- (**) Term: **15 Years**
- (21) Appl. No.: **29/985,965**
- (22) Filed: **Jan. 17, 2025**

(57) **CLAIM**

The ornamental design for a reagent cartridge, as shown and
described.

DESCRIPTION

FIG. 1 is a front, top, and right perspective view of a reagent
cartridge illustrating our new design;
FIG. 2 is a top plan view thereof;
FIG. 3 is a bottom plan view thereof;
FIG. 4 is a left side elevational view thereof;
FIG. 5 is a right side elevational view thereof;
FIG. 6 is a front elevational view thereof;
FIG. 7 is a rear elevational view thereof;
FIG. 8 is a front, top, and left perspective view thereof;
FIG. 9 is a front, bottom, and left perspective view thereof;
and,
FIG. 10 is a front, bottom, and right perspective view
thereof.

The broken lines shown in the drawings illustrate portions of
the reagent cartridge that form no part of the claimed design.
